UNITED STATES PATENT OFFICE

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed October 28, 1930, Serial No. 491,727. Renewed April 9, 1931.

My invention relates to railway traffic controlling apparatus, and has for an object the protection of such apparatus from excessive currents that might be injurious.

5 I will describe two forms of apparatus embodying my invention, and will then point out the novel features thereof in claims.

In the accompanying drawings, Fig. 1 is 10 a diagrammatic view illustrating one form of apparatus embodying my invention. Fig. 2 is a view showing a modified form of part of the apparatus illustrated in Fig. 1 and also embodying my invention.

Similar reference characters refer to similar parts in both views.

Referring first to Fig. 1, the reference character A designates a railway switch which is actuated by an electric motor M having an armature 1 and a field 2. Operatively connected with the switch are cut-out controllers CN and CR. Cut-out controller CN comprises a contact arm 6 and a contact 7, and controller CR comprises a contact arm 3 and a contact 4. Contact 6—7 remains closed at all times except when the switch is in the full reverse position, and contact 3—4 remains closed at all times except when the switch is in the full normal position.

The motor M is controlled in part by a 20 circuit controller P which is in turn controlled by stick relays 76 and 49. The circuit controller P comprises an electro-magnet 9, made up of two windings 9^a and 9^b, and a polarized winding 10 which is preferably provided with a steel permanently magnetized core 11. Pivots attached to the core 11 is an armature 12 which is therefore polarized by flux from the permanent magnet core 11 at such times as winding 10 is not carrying current. It follows that when the electro-magnet 9 is supplied with current of one polarity the armature 12 will be swung in a clockwise direction, but that when current of the opposite polarity is supplied to electromagnet 9 the armature will be swung in the opposite direction. The armature 12 controls three pivoted contact yokes 13, 14 and 15 through suitable linkage, in such manner that the yokes occupy their right-

hand positions when the armature is swung to the left, and vice-versa.

The reference character B designates a neutral magnet which controls a pivoted armature 17, the lower end of which projects into the path of movement of a portion of armature 12 to prevent the reversal of the armature when the neutral magnet B is deenergized. Pivots attached to the armature 17 is a link 19 provided with a slot 43 which at 60 times engages a pin 42 in a rocker arm 70 which carries a contact finger 20. When magnet B is deenergized, the link 19 moves the rocker arm 70 against the bias exerted by a spring 44 into a position in which the contact 65 finger 20 connects wire 33 with wire 34. When neutral magnet B is energized, however, the spring 44 urges the rocker arm 70 into a position wherein the contact between wires 33 and 34 is interrupted.

As shown in the drawings, the switch A occupies its normal position, and the neutral magnet B is deenergized thereby locking armature 12 of circuit controller P in its left-hand position.

The apparatus thus far referred to is illustrated and described in United States Letters Patent No. 1,722,364 granted to Henry S. Young on the 30th day of July, 1929 for railway traffic controlling apparatus.

The reference character R designates an automatic thermal overload circuit breaker. The circuit breaker R comprises a primary core 25 on which is a winding 23, and a secondary core 24 on which is a winding 28. Winding 23 is connected in series with the motor circuit so that it carries the entire motor circuit current. One end of winding 28 is connected to a common terminal for contacts 36 and 32 of stick relays 76 and 49, respectively, and the other end is connected to terminal CH of a source of current. The heating windings 8 and 5 of two thermal relays T¹ and T, respectively, are connected in series with the reverse and the normal motor circuits, respectively, so that the motor circuit current is carried by one of these windings or the other. Contacts 37 and 75 of relays T¹ and T, respectively, are connected in series with relays 49 and 76, respectively, so

85

90

95

100

that if either contact opens, the corresponding relay will be deenergized. Stick relay 76 comprises a winding 48 and contacts 46, 78 and 36, while stick relay 49 comprises a winding 47 and contacts 41, 40 and 32. Contacts 46 and 41 of relays 76 and 49, respectively, are included in the stick circuits of the relays, while contacts 78 and 40 change the polarity of the current supplied to polar relay P, and contacts 36 and 32 control the flow of current through winding 28.

The parts of the circuit breaker R are so designed that as long as coil 28 is energized the maximum amount of current that can be drawn by the switch motor, passing through coil 23, will not attract the armature 21 of coil 23 against the action of coil 28 on armature 26.

The motor circuit, when the switch is to be moved to the reverse position, is from terminal BH, through wire 71, wire 33, contact finger 20, wire 34, winding 23, wire 65, wire 16, yoke 13, flexible connector 67, wire 50, armature 1, wire 51, flexible connector 66, yoke 14, wire 52, winding 8 of thermal relay T¹, contact 7, contact 6, wire 62, wire 64 and field 2 to terminal CH. The pick-up circuit for stick relay 76 is from wire 53, through winding 48, wire 72, contact 74 and contact 75 of thermal relay T to terminal CH. The stick circuit for the same relay is from wire 54, through contact 46, wire 59, winding 76, wire 72, contact 74 and contact 75 to terminal CH. When the switch is to be moved to the normal position from the reverse position, the motor circuit is from terminal BH, through wire 71, wire 33, contact 20, wire 34, winding 23, wire 65, wire 68, yoke 14, flexible connector 66, wire 51, armature 1, wire 50, flexible connector 67, yoke 13, wire 29, winding 5, contact 4, contact 3, wire 63, wire 64 and field 2 to terminal CH. The pick-up circuit for relay 49 is from wire 55, through winding 47, wire 73, contact 38 and contact 37 of thermal relay T¹, to terminal CH. The stick circuit for the same relay is from wire 56, through contact 41, wire 58, winding 47, wire 73, contact 38 and contact 37 to terminal CH.

The holding coil 28 is connected across the field 2 of motor M through wire 64, wire 62, wire 61, either wire 31 or 35, either contact 32 or 36, depending on the contact picked up, wire 30 and winding 28 to terminal CH which is a common terminal for the holding coil 28 and field 2.

When relay 76 is deenergized and relay 49 is energized, neutral magnet B is energized by current through the circuit: from terminal BH, through wire 79, contact 40, wire 95, yoke 15, wire 93, neutral magnet B and wire 94 to terminal CH. When armature 17 is attracted due to the energization of neutral magnet B through this circuit, current will flow through polar relay P from wire 95, through

wire 96, contact 97, wire 98, winding 9^a, wire 99, winding 9^b, wire 100, wire 60, contact 78 and wire 45 to terminal CH. When relay 49 is deenergized and relay 76 is energized, neutral magnet B is energized by current through the circuit: from terminal BH, through wire 77, contact 78, wire 60, yoke 15, wire 93, neutral magnet B and wire 94 to terminal CH. When armature 17 is attracted due to the energization of neutral magnet B through this last circuit, current will flow through polar relay P from wire 60, through wire 100, winding 9^b, wire 99, winding 9^a, wire 98, contact 97, wire 96, wire 95, contact 40 and wire 39 to terminal CH.

In describing the operation of the apparatus, I will assume it is desired to move the switch A to the reverse position. Stick relay 76 is first deenergized and stick relay 49 is energized through its pick-up circuit by a suitable device not embodying my invention and not shown in Fig. 1. Contacts 46, 78 and 36 drop and contacts 41, 40 and 32 are picked up. Neutral relay B is energized because its circuit is closed at contacts 79-40 and armature 17 is attracted, thus, closing suitable contacts to energize and change the polarity of the current supplied to polar relay P. Armature 12 then moves to the right, moving yokes 13, 14 and 15 to the left, closing contacts which complete the reverse motor circuit when armature 17 becomes released to connect wires 33 and 34 through contact finger 20. The switch now moves to the reverse position. If an obstruction occurs in switch A, the motor current will rise above the value necessary to operate relay T¹, and contact 37-38 opens, opening the stick circuit of relay 49. Relay 49 becomes deenergized because the pick-up circuit is also open, and so contact 31-32 will open, opening the circuit of the holding coil 28. With the holding coil deenergized, armature 21 is attracted by energized coil 23 and detent 57 is raised, raising link arm 19 and disengaging slot 43 from pin 42. Rocker arm 70 then moves to the right due to the bias exerted by compressed spring 44, and contact between wires 33-34 opens, opening the motor circuit. The circuit breaker once having been tripped will not reset until the controller P has moved to the opposite position. Resetting controller P is accomplished by energizing stick relay 76 through its pick-up circuit, and when contact 46 is picked up, the relay is energized through the stick circuit. Contact 77-78 then closes the circuit for neutral relay B which attracts armature 17 and moves link arm 19 so that slot 43 engages pin 42. Suitable contacts are closed when armature 17 is attracted to energize and change the polarity of the current supplied to polar relay P. Armature 12 then moves to the left, moving yokes 13, 14 and 15 to the right, closing con-

acts which complete the motor circuit for rotation in the opposite direction when armature 17 is released to connect wires 33 and 34 through contact finger 20. When the switch returns to the normal position, the reverse operation may be repeated as first described, as soon as contact 37—38 of thermal relay T¹ cools sufficiently to close.

In a similar manner if the switch is to be moved from the reverse position to the normal, the stick relay 76 is energized and contacts 46, 78 and 36 are picked up as shown on the drawing. Neutral relay B is energized and armature 17 is attracted, thus closing contacts to energize and change the polarity of the current supplied to polar relay P. Armature 12 then moves to the left, moving yokes 13, 14 and 15 to the right, closing contacts which complete the normal motor circuit when armature 17 is released to connect wires 33 and 34 through contact finger 20. The switch now moves to the normal position. If an obstruction occurs in switch A, the motor current will rise above the value necessary to operate relay T and contact 74—75 opens, opening the stick circuit of relay 76. Relay 76 is deenergized because the pick-up circuit is also open, and contact 35—36 opens, opening the circuit of the holding coil 28. With the holding coil deenergized, armature 21 is attracted by energized coil 23 and detent 57 is raised, raising link arm 19 and disengaging slot 43 from pin 42. Rocker arm 70 then moves to the right due to the bias exerted by compressed spring 44, and contact between wires 33—34 opens, opening the motor circuit. With the circuit breaker tripped it cannot be reset until the controller P has moved to the opposite position. Controller P is reset by energizing stick relay 49 through its pick-up circuit, and when contact 41 is picked up the relay is energized through the stick circuit. Contact 40 closes the circuit for energizing neutral relay B which attracts armature 17 and moves link arm 19 so that slot 43 engages pin 42. Suitable contacts are closed when armature 17 is attracted to energize and change the polarity of the current supplied to polar relay P. Armature 12 then moves to the right, moving yokes 13, 14 and 15 to the left, closing contacts which complete the motor circuit for reverse rotation when armature 17 is released. When the switch moves to the reverse position, the operation may be repeated as before described, as soon as contact 74—75 of thermal relay T cools sufficiently to close.

Referring now to Fig. 2, the circuits for the motor M are the same as before, but controller P is energized and its polarity is changed by a polarized relay 80 instead of the two stick relays 76 and 49. In Fig. 1, the operation of one of the thermal relays will deenergize the associated stick relay and thus

open the holding coil circuit, while in Fig. 2 the holding coil circuit opens when either thermal relay operates.

The holding coil 28 is connected across field 2 of motor M by either one of two circuits depending on the position of contact 89 of polarized relay 80. When switch A is moving to the reverse position, the holding coil 28 is connected across field 2 through wire 64, wire 62, wire 69, contact 37, contact 38, wire 73, contact 89, wire 30, winding 28 and to terminal CH which is a common terminal for the holding coil 28 and field 2. When switch A is moving to the normal position, the holding coil 28 is connected across field 2 through wire 64, wire 63, wire 71, contact 75, contact 74, wire 72, contact 89, wire 30 and winding 28 to terminal CH.

When winding 81 of polar relay 80 is energized by current of such polarity that the polar contacts 87, 88 and 89 move to the right, neutral magnet B will be energized through a circuit from terminal BH, through contact 82, wire 83, contact 87, wire 90, wire 95, yoke 15, wire 93, neutral magnet B and wire 94 to terminal CH. When armature 17 is attracted due to the energization of neutral magnet B through this circuit, current will flow through polar relay P from wire 95, through wire 96, contact 97, wire 98, winding 9^a, wire 99, winding 9^b, wire 100, wire 60, wire 92, contact 88, wire 84 and contact 85 to terminal CH. When winding 81 of polar relay 80 is energized by current of such polarity that the polar contacts are swung to the left, neutral magnet B is energized through the circuit from terminal BH, through contact 82, wire 83, contact 87, wire 86, wire 60, yoke 15, wire 93, neutral magnet B and wire 94 to terminal CH. When armature 17 is attracted due to the energization of neutral magnet B through this last circuit, current will flow through polar relay P from wire 60, through wire 100, winding 9^b, wire 99, winding 9^a, wire 98, contact 97, wire 96, wire 95, wire 91, contact 88, wire 84 and contact 85 to terminal CH.

The operation of switch A in Fig. 2 is similar to the operation of the switch in Fig. 1, except that instead of relays 76 and 49 controlling the operation of the switch to the reverse and normal position as in Fig. 1, the polar relay 80 controls the operation of the switch in Fig. 2.

With apparatus embodying my invention, it is possible to restore the switch movement to its last operated position immediately and to attempt to operate the movement again in the direction in which it failed as soon as the thermal relay for that direction has cooled off so as to complete the holding coil circuit.

Although I have herein shown and described only two forms of apparatus embodying my invention, it is understood that various changes and modifications may be made

therein within the scope of the appended claims without departing from the spirit and scope of my invention.

Having thus described my invention, what I claim is:

1. In combination, a railway switch, an electric motor for operating said switch, a normal and a reverse thermal relay each including a heating winding and a normally closed contact, a normal and a reverse circuit for said motor including the heating windings of said normal and reverse thermal relays respectively, two circuit controllers, one included in said normal circuit and closed in all positions of the switch except the reverse and the other included in said reverse circuit and closed in all positions of the switch except the normal, a circuit breaker having a first and a second core for controlling the supply of current to said motor, a winding on the first core of said circuit breaker included in both of said circuits and constituting a means for tripping said circuit breaker, a holding winding on the second core of said circuit breaker connected across the field of said motor and when energized acting to prevent tripping of said circuit breaker, a normal and a reverse stick relay for closing one or the other of said circuits to cause rotation of the motor in one direction or the other, and a pick-up and a stick circuit for each of said stick relays each circuit including the contact of the associated thermal relay.
2. In combination, a railway switch, an electric motor for operating said switch, a normal and a reverse thermal relay, each including a heating winding and normally closed contact, a normal and a reverse circuit for said motor including the heating windings of said normal and reverse thermal relays respectively, two circuit controllers one included in said normal circuit and closed in all positions of the switch except the reverse and the other included in said reverse circuit and closed in all positions of the switch except the normal, a circuit breaker having a first and a second core for controlling the supply of current to said motor, a winding on the first core of said circuit breaker included in both of said circuits and constituting a means for tripping said circuit breaker, a holding winding on the second core of said circuit breaker connected across the field of said motor and when energized acting to prevent tripping of said circuit breaker, a polarized relay including a polarized contact, two control circuits for said holding winding each circuit at times including said polarized contact depending on the position of the contact due to the polarity of said polarized relay, and governing means included in each of said motor circuits and responsive to the magnitude of the current supplied to said motor for governing one of said relays or the other.
3. In combination, an electric motor, a normal and a reverse operating circuit for said motor, a circuit breaker for controlling the supply of current to said motor having a first and a second core, a winding on said first core included in both of said motor circuits and constituting a means for tripping said circuit breaker, a holding winding on said second core acting when energized to prevent tripping of said circuit breaker, a normal and a reverse relay for energizing said holding winding and for closing one or the other of said motor circuits to cause rotation of the motor in one direction or the other, and governing means included in each of said motor circuits and responsive to the magnitude of the current supplied to said motor for governing one of said relays or the other.
4. In combination, an electric motor, a normal and a reverse operating circuit for said motor, a circuit breaker for controlling the supply of current to said motor, a first winding included in both of said motor circuits and constituting a means for tripping said circuit breaker, a second winding acting when energized to prevent tripping of said circuit breaker, a normal and a reverse relay for energizing said second winding and for closing one or the other of said motor circuits to cause rotation of the motor in one direction or the other, and governing means included in each of said motor circuits and responsive to the magnitude of the current supplied to said motor for governing one of said relays or the other.
5. In combination, an electric motor, a normal and a reverse operating circuit for said motor, a circuit breaker for controlling the supply of current to said motor having a first and a second core, a winding on said first core included in both of said motor circuits and constituting a means for tripping said circuit breaker, a holding winding on said second core acting when energized to prevent tripping of said circuit breaker, a polarized relay including a polarized contact, two control circuits for said holding winding each circuit at times including said polarized contact depending on the position of the contact due to the polarity of said polarized relay, and governing means included in each of said motor circuits and responsive to the magnitude of the current supplied to the motor for governing one of said control circuits or the other.
6. In combination, an electric motor, a normal and a reverse operating circuit for said motor, a circuit breaker for controlling the supply of current to said motor, a first winding included in both of said motor circuits and constituting a means for tripping said circuit breaker, a second winding acting when energized to prevent tripping of said circuit breaker, a polarized relay including a polarized contact, two control circuits for said second winding each circuit at times including said polarized contact depending on the position of the contact due to the polarity of said polarized relay.

on the position of the contact due to the polarity of said polarized relay, and governing means included in each of said motor circuits and responsive to the magnitude of the current supplied to the motor for governing one of said control circuits or the other.

7. In combination, an electric motor, a normal and a reverse operating circuit for said motor, a circuit breaker for controlling the supply of current to said motor having a first and a second core, a winding on said first core included in both of said motor circuits and constituting a means for tripping said circuit breaker, a normal and a reverse relay for closing one or the other of said motor circuits, respectively, to cause rotation of the motor in one direction or the other, means controlled in turn by one or the other of said relays for governing the flux in said second core to prevent said circuit breaker from tripping, and governing means included in each of said motor circuits and responsive to the magnitude of the current supplied to said motor for governing one of said relays or the other.

8. In combination, an electric motor, a normal and a reverse operating circuit for said motor, a circuit breaker for controlling the supply of current to said motor having a first and a second core, a winding on said first core included in both of said motor circuits and constituting a means for tripping said circuit breaker, a polarized relay including a polarized contact, means for governing the flux in said second core to prevent said circuit breaker from tripping, two control circuits for said means, each circuit at times including said polarized contact depending on the position of the contact due to the polarity of said polarized relay, and governing means included in each of said motor circuits and responsive to the magnitude of the current supplied to the motor for governing one of said control circuits or the other.

9. In combination, a railway switch, an electric motor for operating said switch, a normal and a reverse thermal relay each including a heating winding and a contact, a normal and a reverse circuit for said motor including the heating windings of said normal and reverse thermal relays respectively, two circuit controllers, one included in said normal circuit and closed in all positions of the switch except the reverse and the other included in said reverse circuit and closed in all positions of the switch except the normal, a circuit breaker having a first and a second core for controlling the supply of current to said motor, a winding on the first core of said circuit breaker included in both of said circuits and constituting a means for tripping said circuit breaker, a holding winding on the second core of said circuit breaker connected across the field of said motor and when energized acting to prevent tripping of said circuit breaker, a normal and a reverse relay for closing one or the other of said circuits, respectively, to cause rotation of the motor in one direction or the other, and a pick-up circuit for each of said relays, each circuit controlled by the contact of the thermal relay associated therewith.

cuit breaker, a normal and a reverse relay for closing one or the other of said circuits, respectively, to cause rotation of the motor in one direction or the other, and a pick-up circuit for each of said relays, each circuit controlled by the contact of the thermal relay associated therewith.

10. In combination, an electric motor, a normal and a reverse operating circuit for said motor, a circuit breaker for controlling the supply of current to said motor, a first winding included in both of said motor circuits and constituting a means for tripping said circuit breaker, a second winding acting when energized to prevent tripping of said circuit breaker, a normal and a reverse relay for energizing said second winding and for closing one or the other of said motor circuits to cause rotation of the motor in one direction or the other, and thermal means included in each of said motor circuits and responsive to the magnitude of the current supplied to said motor for governing one of said relays or the other.

11. In combination, a electric motor, a normal and a reverse operating circuit for said motor, a circuit breaker for controlling the supply of current to said motor, a first winding included in both of said motor circuits and constituting a means for tripping said circuit breaker, a second winding acting when energized to prevent tripping of said circuit breaker, a polarized relay including a polarized contact, two control circuits for said second winding each circuit at times including said polarized contact depending on the position of the contact due to the polarity of said polarized relay, and thermal means included in each of said motor circuits and responsive to the magnitude of the current supplied to the motor for governing one of said control circuits or the other.

12. In combination, an electric motor, an operating circuit for said motor, a circuit breaker for controlling the supply of current to said motor, a tripping winding included in said motor circuit and constituting a means for tripping said circuit breaker, a holding winding acting when energized to prevent said circuit breaker from tripping, a relay for governing said operating circuit and for energizing said holding winding, and means included in said motor circuit and responsive to the magnitude of the current supplied to said motor for governing said relay.

13. In combination, an electric motor, an operating circuit for said motor, a circuit breaker for controlling the supply of current to said motor, a tripping winding included in said motor circuit and constituting a means for tripping said circuit breaker, a holding winding acting to prevent said circuit breaker from tripping, a relay for governing said operating circuit and for controlling said holding winding, and means included in said

motor circuit and responsive to the magnitude of the current supplied to said motor for modifying the control of said holding winding by said relay.

14. In combination, an electric motor, an operating circuit for said motor, a circuit breaker for controlling the supply of current to said motor, a tripping winding included in said motor circuit and constituting a means

10 for tripping said circuit breaker, a holding winding acting when energized to prevent said circuit breaker from tripping, a relay for governing said operating circuit and for energizing said holding winding, and means responsive to the magnitude of the current supplied to said motor for governing said relay.

15. In combination, an electric motor, an operating circuit for said motor, a circuit breaker for controlling the supply of current to said motor, a tripping winding included in said motor circuit and constituting a means for tripping said circuit breaker, a holding winding acting to prevent said circuit breaker from tripping, a relay for governing said operating circuit and for controlling said holding winding, and means responsive to the magnitude of the current supplied to said motor for modifying the control of said holding winding by said relay.

16. In combination, an electric motor, an operating circuit for said motor, a circuit breaker for controlling the supply of current to said motor having a first and a second core, an operating winding on said first core included in said motor circuit and constituting a means for tripping said circuit breaker, governing means for governing the flux in said second core to prevent said circuit breaker from tripping, a relay for controlling said operating circuit and said governing means, and means included in said motor circuit and responsive to the magnitude of the current supplied to said motor for governing said relay.

17. In combination, an electric motor, an operating circuit for said motor, a circuit breaker for controlling the supply of current to said motor having a first and a second core, an operating winding on said first core included in said motor circuit and constituting a means for tripping said circuit breaker, governing means for governing the flux in said second core to prevent said circuit breaker from tripping, a relay for controlling said operating circuit and said governing means, and means included in said motor circuit and responsive to the magnitude of the current supplied to said motor for modifying the control of said governing means by said relay.

18. In combination, an electric motor, an operating circuit for said motor, a circuit breaker for controlling the supply of current to said motor having a first and a second core, an operating winding on said first core in-

cluded in said motor circuit and constituting a means for tripping said circuit breaker, governing means for governing the flux in said second core to prevent said circuit breaker from tripping, a relay for controlling said operating circuit and said governing means, and means responsive to the magnitude of the current supplied to said motor for governing said relay.

19. In combination, an electric motor, an operating circuit for said motor, a circuit breaker for controlling the supply of current to said motor having a first and a second core, an operating winding on said first core included in said motor circuit and constituting a means for tripping said circuit breaker, governing means for governing the flux in said second core to prevent said circuit breaker from tripping, a relay for controlling said operating circuit and said governing means, and means responsive to the magnitude of the current supplied to said motor for modifying the control of said governing means by said relay.

In testimony whereof I affix my signature.

ROBERT M. GILSON.
